UNITED STATES PATENT OFFICE.

ARTHUR WELLINGTON McMAUGH AND ROBERT WELCH, OF ST. CATHERINES, ONTARIO, CANADA.

ELECTRIC RAILROAD-SIGNAL.

No. 895,035.

Specification of Letters Patent.

Patented Aug. 4, 1908.

Application filed December 3, 1906. Serial No. 346,148.

To all whom it may concern:

Be it known that we, ARTHUR WELLINGTON McMAUGH and ROBERT WELCH, both of the city of St. Catharines, in the county 5 of Lincoln, in the Province of Ontario, Canada, have invented certain new and useful Improvements in Electric Railroad-Signals, of which the following is the specification.

- 10 Our invention relates to improvements in electric signals for railroads, and the object of the invention is to provide a simple, cheap, positively acting device, whereby the engineers or conductors of any train on the 15 track may be apprised immediately when he comes within the block or zone occupied by another train whether the trains be approaching each other from opposite direction or running in the same direction.
- 20 A further object is to enable the engineer or conductor to signal each other in the trains, which are approaching, so as to indicate in which direction the trains are going and thus further obviate any danger of 25 collision.

To carry out these objects our invention consists of a track provided with a sectional center rail, which extends from end to end of the danger zone, and engines or other 30 motors each of which is provided with a contact shoe spring-held against the third rail, an electric circuit having a bell and switch and circuit changer all operatively arranged in series and connected to the axle 35 of the car at one end and to the shoe at the opposite end, so that when two engines or motors are in the danger zone these electrical apparatus are in series, the parts being arranged and constructed in detail as 40 hereinafter more particularly explained.

Figure 1, is a plan view showing diagrammatically two engines or motors on a track within the danger zone. Fig. 2, is a sectional elevation. Fig. 3, is a cross section 45 showing the contact of the shoe with the third rail.

In the drawings like letters of reference indicate corresponding parts in each figure.

A A are the ordinary rails of the track.

50 B is a center sectional rail, which is preferably an ordinary rail reversed and held in suitable brackets C, the flange being uppermost.

The rails A are connected by suitable

means from end to end, so as to form a path 55 for the electric current.

D is a semi-elliptical spring attached to a cross beam E secured to the bottom of the body of the locomotive or other motor-car. The beam E is suitably insulated.

60 F is a shoe, which is turned up at each end and is provided with an upper-plate F', both plates being secured to the center of the spring D.

G are the axles of the car and G' the 65 wheels.

H is a brush running against the sleeve I attached to the axle G.

J is a wire leading from a binding post on the shoe F to and through a gong K being 70 connected to the lever switch L. The wire J extends from the switch L to a binding post 2 on the plate M, which forms one of the parts of the pole changer, the opposite end of which also consists of a plate M' 75 having a binding post 2', which is connected by a wire J' to the brush H.

J² is a wire leading from one plate M to the other and having in its path the battery J³.

80 N is the pole changer, the ends of which are designed to be brought in contact alternately with the plates M and M'. The pole changer N is provided with a suitable handle N' and is journaled in suitable bearings as 85 indicated. It is also essential that the pole changer be manipulated so as to change the polarity of the battery in the cab to correspond to the polarity of the battery in the 90 cab of the approaching train and it necessarily follows that at the end of each run the locomotive or cab or car will have to have the polarity of the battery changed prior to its starting along the track in the opposite direction.

95 It will now be noticed especially on reference to Fig. 1, that as soon as two trains or cars get on the same rail or track, that the passage of the current is from the shoes through the wire J switch L battery and pole changer along the wire J' through the brush H to the axle G, thence by the wheels G' and rails A to the wheel G' of the cab of the locomotive or motor car on the same danger zone, thence by the brush H wire J' circuit plate M batteries switch L and gong and wire J to the shoe F and rail B, whereby the 100 circuit is completed. It will thus be seen that 105

immediately two trains get on to the danger zone, that is the portion of the track provided with the center rail B, that the other engine or car will likewise be apprised of the 5 same by the ringing of the gongs K.

In order to insure that the engineer of the approaching train may know which way such train is going the switch L may be thrown out as often as desired to give the 10 desired signal to the engineer or conductor of the approaching train as to the whereabouts of such train.

By such an electric signal as we have devised we are enabled to insure against any 15 danger of collision.

What we claim as our invention is:

1. In an electric signaling apparatus, the combination with a track, of a sectional center rail, a U shaped spring extending trans- 20 verse the track and having its ends connected to the bottom of the car, a shoe carried by said spring and extending transverse thereof and engaging the third rail, an alarm and

switch in electrical connection with the shoe, an electrical connection with the wheel of the 25 car, a battery, an oscillating pole changer connected to the poles of the battery and connecting the wheel connection and switch connection.

2. In an electric signaling apparatus, the 30 combination with a track, of a sectional center rail, a spring secured to the bottom of the car, a shoe carried by said spring and contacting with the third rail, an alarm, and a switch in electric connection with said shoe, 35 a plate M in electric connection with the switch, a second plate M', a rotary piece N having secured to each end thereof a plate adapted to engage the plates M and M' respectively and having connected thereto a 40 battery, substantially as described.

ARTHUR WELLINGTON McMAUGH.

ROBERT WELCH.
